F. E. DAYTON.
DISPENSING AND MEASURING PUMP.
APPLICATION FILED OCT. 23, 1917.

1,277,699.

Patented Sept. 3, 1918.

UNITED STATES PATENT OFFICE.

FRANK E. DAYTON, OF LOS ANGELES, CALIFORNIA.

DISPENSING AND MEASURING PUMP.

1,277,699.

Specification of Letters Patent. Patented Sept. 3, 1918.

Application filed October 23, 1917. Serial No. 192,052.

To all whom it may concern:

Be it known that I, FRANK E. DAYTON, a citizen of the United States, residing at Los Angeles, in the county of Los Angeles and State of California, have invented new and useful Improvements in Dispensing and Measuring Pumps, of which the following is a specification.

This invention relates to dispensing and measuring pumps, and more particularly to improvements in housings for such pumps of the type which is stationed out of doors and is thus subjected to the elements and tampering with by unauthorized persons, the primary object of the invention being the provision of a housing which is constructed so that access to the mechanism which it houses, for the purposes of inspection or repair thereof, is permitted readily, and without requiring disassembling of the pump.

In the majority of dispensing apparatus, particularly dispensing and measuring pumps which are stationed out of doors and have casings or housings protecting the pump mechanism, the housings or casings are constructed in such a manner that it is necessary to completely disassemble the pump, and in the majority of instances to remove the pump from its supporting base, in order to gain access to the pump mechanism or parts for the purpose of inspection, repair or renewal of parts thereof. Therefore the repair, inspection or renewal of parts of pump mechanism in dispensing apparatus of this type, is annoying, consumes a great deal of time, requires a great deal of labor and is generally otherwise objectionable. My invention entirely overcomes the above-noted objections in a reliable, economical and facile manner. To this end my invention consists in the provision of a sectional housing, the lower or base section of which instead of being stationary, as is generally the case, is movable and can be elevated into position to allow access to the pump mechanism which it houses when in down position; and, my invention further consists in the particular coöperation and association of this movable lower or base section of the housing, with the upper section of the housing, which upper section is movable so that it will serve when in up position to house and protect the upper or operating mechanism for the pump, and

when in down position will permit access to said upper or pump operating mechanism.

With the above and other objects in view, the invention further consists in the novel and useful provision, formation, construction, combination, association and interrelation of parts, members and elements, all as hereinafter described, shown in the drawing and finally pointed out in claims.

In the drawing:

Figure 1 is a vertical sectional view partly in elevation of a dispensing apparatus constructed in accordance with the invention showing the apparatus in locked position;

Fig. 2 is a side elevation of the pump broken away and partly in section, illustrating the movable lower section of the housing in elevated position so as to permit access to the pump elements;

Fig. 3 is a side elevation of the pump broken away at one corner and showing it as it would appear ready for service;

Fig. 4 is a detail fragmentary sectional view of a part of the pump capacity control means.

Referring particularly to the drawing forming a part of this application and in which like parts are designated by like characters, throughout the several views, 1 generally designates the housing forming the subject-matter of this invention, and 2 the measuring and dispensing apparatus which is disposed within the housing 1. The dispensing apparatus 2 comprises a measuring cylinder 3, a filter 4 operatively associated therewith, a service pipe 5 connected with the filter, pump mechanism 6 operatively associated with the cylinder 3, a liquid supply pipe 7 connected with the cylinder 3, a skeleton frame 8 for supporting the dispensing apparatus, a dome 9 supported upon the upper end of the frame 8 and a light globe 10 supported upon the upper end of the dome 9 and having suitable illuminating means, not shown therein. The frame 8 comprises vertical standards 11 which at their lower ends are connected with a base casting 12, and at their upper ends with the dome 9, said upper ends being screw-threaded as at 13 and turned into screw-threaded openings 14 formed in the dome 9. Intermediate and approximately central of the ends of the standards 11 a pump mechanism supporting casting 15 is located, said casting being provided with openings 16 through which the stand-

100

105

110

ards 11 extend. The casting 15 rests upon the upper ends of tubular standards 17 which surround and receive the standards 11, the lower ends of said tubular standards 17 being disposed within the counter-bored portions 18 of the base casting 12. The standards 11 extend through the base casting 12 and have nuts 19 turned on their lower ends. Pins 20 are inserted transversely through the standards 11 and are adapted to engage the upper side of the casting 15 so that when the nuts 19 are screwed up upon the standards 11 said pins 20 will tend to force the casting 15 into firm engagement with the upper ends of the standards 17. In addition to the standards 11 and 17 there is provided a supporting rod and tube 21 and 22, respectively. The rod 21 is fixedly engaged with the casting 15 and extends through the base casting 12 as do the standards 11. In this connection it will be noted that the body portion of the base casting 12 is spaced from the surface upon which the apparatus is supported by an annular depending flange 23 formed at the periphery of the base. A nut 24 is turned upon the lower end of the rod 21, and the tube 22 surrounds and receives the rod 21, such tube serving to support the casting 15 as do the tubular standards 17.

The measuring cylinder 3 is suitably connected with and depends from the casting 15 and the filter 4 is likewise connected with the casting. As a means for supporting the cylinder there are provided series of rods 25 which are fixedly secured to the casting 15 and extend downwardly therefrom along the outer side of the cylinder to a point below the lower end of the latter. A spider 26 supporting member 26 is connected with the lower ends of the rods 25 and rests against the lower end of the cylinder, there being provided nuts 27 turned upon the screw-threaded ends 28 of the rods 25 and into engagement with the spider 26 so as to hold the latter in position, and to likewise provide for the ready removal of the spider and cylinder for the purpose of inspection, repair or renewal of parts thereof, or of parts operatively associated therewith. An easily operable coupling member 29 is provided for connecting the supply pipe 7 with the casting 30 forming the lower part of the cylinder 3. Utilization of this type of coupling provides for an expeditious assembling or disassembling of the pump. There is provided a head casting 31 which is connected with the casting 15 and together with said casting supports the mechanism 2 for operating the pump, such mechanism including a rack bar piston rod 32 operatively associated with the cylinder 3 and capacity regulating means generally designated 33. It is not thought necessary to specifically 65 and in detail describe the pump operating

mechanism which is of conventional form, with the exception of the capacity control means 33. The means 33 comprises a rotatably mounted vertically disposed rod 34 which is rotatably journaled as at 35 at its upper end within a web portion 36 of the head casting 31, and at its lower end it is rotatably mounted within a socket 37 therefore formed in the casting 15. A spring 38 is mounted within the socket 37 and is interposed between the lower end of the rod 34 and the socket 37 so as to provide for frictionally holding the rod in adjusted position. Stop lugs 39 and 40 are fixed at predetermined points upon the rod 34, and extend in opposite directions horizontally from said rod, there being pins 41 that are inserted transversely through the lugs and rod to hold the lugs in place. A stop element or lug 42 is fixed to the rack bar 32 and adapted for coöperation with either of the lugs 39 or 40. As shown in Fig. 1 of the drawing the lug 39 is disposed in an out of the way position and the lug 40 is disposed in operative position so that when the piston rod rack bar 32 has been moved a predetermined distance so as to cause a predetermined amount of liquid to enter the cylinder 3 the lug 42 thereon will engage an adjusting screw 43 which is carried by the lug 40, and the operation, that is, the further movement of the rack bar 32 is prevented. A screw 44 is provided for the lug 39, said screws 43 and 44 providing for the desired regulation of dispensation of liquid operated upon by the pump. By turning the rod 34 the lug 39 may be brought into place and the lug 40 is then disposed in an out of the way position. The lug 39 will then coöperate with the stop 42 to limit the movement of the piston rod and operation of the pump.

The housing 1 for the apparatus hereinbefore described, comprises a lower movable and preferably cylindrical section 45 and an upper preferably cylindrical section 46 that is likewise movable and is adapted to telescope the lower section 45. The base casting 12 is counter-bored as at 47 to receive the lower edge of the housing section 45 and the casting 15 preferably fits snugly within the upper end of the section 45, said upper end terminating preferably flush with the upper surface of the casting. In this connection it will be noted that the casting 15 at its periphery is disposed beyond the standards 17 and 22, thus the housing section 45 is circumferentially spaced from the frame 8, that is, the standards 17 and 22.

The upper housing section 46 is provided exteriorly near its upper end and upon opposite sides with the handles 49 and with a latch bar 50 which is located at and extends above the upper end thereof. This latch bar 50 is adapted to coöperate with a key

lock 51 carried by the dome 9 and when in the position shown in Fig. 1 of the drawing, locks the housing 46 in position to protect the mechanism 2 against the elements 6 and pillage or being tampered with by unauthorized persons. When this upper section 46 is in position shown in Fig. 1 it overlies the upper portion of the section 45 so as to prevent rain from entering the 10 housing. We are aware that housings comprising a movable upper section such as the one 46 forming a part of our invention have been used heretofore, but I consider the movable lower section 45 the essence of my 15 invention and in the use of my invention when it is necessary to inspect the pump piston, not shown, any of the filter parts, not shown, or any of the parts or coöperative parts of the pump, it is only necessary to 20 raise the housing section 45 into the position shown in Fig. 2 of the drawing. When the housing section 45 is thus raised access to the pump parts is readily had, whereas in pumps of the type heretofore known and 25 now in use the housing for the lower part of the pump mechanism is stationary as mentioned hereinbefore. To hold the housing section 45 in up position there is provided a rotatable supporting lug 52 mounted upon 30 the tubular standard 22. This lug 52 may be readily turned into or out of supporting position, and when in supporting position the section 45 rests thereon.

With reference to the foregoing description and the accompanying drawing, the operation and method of use of my invention will be readily apparent, and it is to be understood that various changes as to size, shape and as to details of construction of 40 the parts of my invention may be resorted to when required, without departing from the spirit and scope of the invention as defined.

Having thus disclosed my invention, I claim and desire to secure by Letters Patent:

45 1. In improvements of the character disclosed, a base, a frame extending upwardly from the base, dispensing mechanism supported by the frame, and a housing for the mechanism surrounding said frame and 50 mechanism and being movable up and down relative thereto; said housing comprising relatively movable sections.

55 2. In improvements of the character disclosed, a base, a frame extending upwardly from the base, dispensing mechanism supported by the frame, and a housing for the mechanism surrounding said frame and mechanism and being movable up and down relative thereto; said housing comprising 60 relatively movable sections, the upper of which is adapted to telescope the lower.

3. In apparatus of the character disclosed, upright dispensing mechanism and a housing surrounding said mechanism and being 65 movable relative thereto so as to reveal and

permit access to any portion thereof; said housing consisting of upper and lower relatively movable sections.

4. In improvements of the character disclosed, upright dispensing mechanism including a base and a dome located adjacent to its upper end, a housing in sections and surrounding the dispensing mechanism, means whereby one of the sections of the housing may be locked to the dome, the other 70 section of the housing normally resting upon the base and extending into the lower end of the upper section, said lower section being movable upwardly to permit access to the mechanism and said upper section adapted 75 to be lowered to likewise permit access to the mechanism.

5. In apparatus of the character disclosed, upright dispensing mechanism including a base and a dome adjacent to its upper end, 80 a housing in sections and surrounding the dispensing mechanism, means whereby one of the sections of the housing may be locked to the dome, the other section of the housing normally resting upon the base and extending 85 into the lower end of the upper section, said lower section being movable upwardly to permit access to the mechanism and said upper section adapted to be lowered to likewise permit access to the mechanism; and 90 means to hold the lower section in elevated position.

6. In apparatus of the character disclosed, upright dispensing mechanism, a base upon which said mechanism is mounted, standards 100 secured to and extending upwardly from the base, said mechanism being supported by the standards, a dome supported by the standards above the mechanism, an upper housing surrounding the standards and upper part of the mechanism, means to lock said upper housing to the dome, and a lower housing normally resting upon the base and surrounding the mechanism, said lower housing extending into the lower end of the 105 upper housing and being movable upwardly to permit access to the mechanism normally housed thereby.

7. In apparatus of the character disclosed, a base member, upright standards connected 110 with the base member, a casting supported upon the standards, dispensing apparatus connected with the casting, a housing normally resting upon the base and surrounding the standards and a part of the dispensing mechanism, said housing terminating at a point substantially in line with the casting, and another housing surrounding the standards and upper part of the mechanism and telescoping said first named housing, 115 said first named housing being movable upwardly into the second named housing and said second named housing being lowerable over the first named housing.

8. In improvements of the character dis- 120

- closed, a base member, upright standards connected with the base member, tubular standards receiving the upright standards and resting upon the base member, a casting 5 having apertures receiving the upright standards, said casting resting upon the upper ends of the tubular standards, dispensing mechanism supported by the casting, and a housing receiving the mechanism and 10 standards and normally resting upon said base member, said housing being movable upwardly to permit access to that portion of the dispensing mechanism which it normally houses.
- 15 9. In improvements of the character disclosed, a base member, upright standards connected with the base member, tubular standards receiving the upright standards and resting upon the base member, a casting 20 having apertures receiving the upright standards, said casting resting upon the upper ends of the tubular standards, dispensing mechanism supported by the casting, a housing receiving the mechanism and standards and normally resting upon said base 25 member, said housing being movable upwardly to permit access to that portion of the dispensing mechanism which it normally houses, and an upper housing adapted to telescope the first named housing, and means 30 carried by the upright standards for co-operation with said last named housing to provide for the holding of the latter in up position.
10. In improvements of the character disclosed, a base member, upright standards connected with the base member, a dome supported upon the upper ends of the upright standards, dispensing mechanism, means associated with the upright members 35 to support the mechanism, a housing in sections and which incloses the uprights and dispensing mechanism, one of the sections of the housing being adapted to extend into the lower side of the dome, means to lock 40 said section of the housing in such relation to the dome, the other section of the housing normally resting upon the base member and being movable upwardly into the first named housing to permit access to the mechanism 45 normally housed thereby.
- In testimony whereof I have signed my name to this specification in the presence of two subscribing witnesses.
